SLIDING AND ROTATING ATTACHED
CLOSURE FOR TOOTH PASTE TUBES

Frank G. Seibel, Claremont, Calif.

Application December 9, 1947, Serial No. 790,447

2 Claims. (Cl. 222—92)

1
This invention pertains to sliding and rotating attached closures for tooth paste tubes, or the like, and has for its objects,

First, the provision of a tooth paste tube closing device which will function to close or open the tube without being detached;

Second, the provision of a tooth paste tube closing device which has a slidable and rotatable plug with shearing surfaces adapted to cleanly shut off flow of paste from the tube to prevent hardening in, or clogging of the passageways;

Third, a tooth paste closing device which has a plug longitudinally slidable in a boss formed at the end of the tube arranged to open a hole formed in the side of the tube when the plug is partially withdrawn, to close said plug when the plug is forced inward, and to lock in closed position by a partial rotation of the plug.

Other objects include the arrangement of the above mentioned parts so that the flow of paste is direct and not tortuous, and so that on each closure the paste is moved away from the delivery orifice to prevent drying or clogging, and provide a definite agitation of paste adjacent the delivery orifice during each opening or closing movement; and

Still another object is to provide a closure, as above stated, which can be made easily and cheaply, which is easily assembled, and which is easy and positive in its operation.

Other objects will appear hereinafter.

I attain the foregoing objects by means of the devices shown in the accompanying drawing in which—

Figure 1 is a frontal side elevation of the top of the upper portion of a tooth paste tube showing my closure in closed position;

Figure 2, a similar view, but with portions of the tubes and tube boss broken away to show the structure of the plug;

Figure 3, a side elevational view of the back of the tube body with the tube portions sectioned off and showing the closing plug rotated to unlocked position;

Figure 4, a similar rear view with the plug moved outward to opened position;

Figure 5, a perspective view of the tube boss and the closing plug in position ready for assembly;

Figure 6, a section taken on line 6—6, Figure 1, showing the relation of the plug and boss when these parts are in closed position as in Figure 1;

Figure 7, a similar sectional view with the plug moved to unlocking position, as also shown

in Figure 2 and Figure 8, a section taken on line 8—8, Figure 4, with the plug extended to open position.

Similar numerals refer to similar parts in the several views.

The tube 2 is made with a tubular boss 3 centrally positioned on its closed end into which closing plug 4 is fitted.

The lower portion 6 of plug 4 is cylindrical and is sized to fit into boss 3 with a free but fairly tight working fit. This cylindrical portion is free to slide in and out axially, as well as to rotate. At the top of this cylindrical portion 4 there is a knurled disc 7, which forms a gripping knob. These two portions are made integral from one piece of material.

A square hole 10 is formed in the side of boss 3. A diametrically extending notch 12 is formed on the inner face of plug portion 6. It is sized to register with hole 10 when the plug is moved to the proper rotative and axial position.

At diametrically opposite positions on each side of plug portion 6 inverted L-shaped grooves 14 are formed.

25 Boss forming indentations 16 are pressed into the outer wall sides of boss 3 to form inwardly extending retaining bosses 17 on its interior. These are positioned and spaced relative to grooves 14, and, in turn, relative to delivery hole 10 so that plug 4 will be held with one end of notch 12 alined to register with hole 10 during the inner sliding motion of plug 4, and so that when the plug is slid out to the limit of travel of bosses 17 in the vertical portions of grooves 14, one end of notch 12 is fully in register with hole 10. The horizontal arms of grooves 14 are positioned so that, when the plug is fully inserted, with notch 12 below the plane of hole 10, the plug can be rotated with bosses 17 sliding horizontally in the horizontal portions of grooves 14. This provides a lock to prevent the plug from being pulled out from closed position, or from being forced out by compression of substance in the tube.

40 The parts are assembled as shown particularly in Figure 5. The tube is made from metal or other suitable material in the usual manner. The tube neck or boss 3 is then punched to form hole 10. The plug 4, formed preferably of plastic, is then inserted in the boss and indentations 50 provide effective means for permanently holding the plug in place.

When it is desired to remove paste from the tube, plug 4 is first rotated counter-clockwise as indicated by the arrow, Figure 3. At substantially the same time, and by the same motion, it

is withdrawn as indicated by the arrow, Figure 4. These two simple motions unlock the plug and open the discharge hole 10. After paste has been used, as desired, the hole is closed first, by sliding the plug inward and then, by turning it clockwise to lock it in closed position.

While I have specified certain materials and certain uses, I intend that these are exemplary only, and point out that many different materials may be used, and also, that the specific structure mentioned may be substantially modified and still remain within the spirit and intentions of the invention. While I have indicated that toothpaste is contained in tube 2, it is obvious that any other substance of substantially equivalent consistency may be contained by the tube and dispensed through my, above described, closing device.

In view of the foregoing, I wish to be limited only by the following claims.

I claim:

1. A closing device for toothpaste tubes comprising a tubular boss formed on the closed end thereof having a peripheral discharge hole; a closing plug axially and rotatably operative therein, inverted L-shaped grooves positioned diametrically opposite formed on the periphery of said plug, and a diametrically extending notch cut in the inner face thereof; and inwardly extending retaining bosses formed on the inner faces of the walls of said tubular boss, adapted to operatively engage in said L-shaped plug grooves, and positioned to retain said plug in fully inserted closed position by partial rotation of said plug in said boss, and to guide said plug when it is withdrawn so that said plug notch is maintained with an end in registering alignment with said discharge hole, and to limit outward

axial movement of said plug when said notch is fully in register with said discharge opening.

2. A closing device for toothpaste tubes, or the like, comprising, in combination, a collapsible tube having a closed end, a tubular boss opening from said tube and formed on said closed end; a peripheral discharge hole formed in said boss; a closing plug having a knob at its outer end and a cylindrical inner portion rotatable and axially slid able in said tubular boss; a diametrical notch formed on the inner face of said plug, and diametrically opposite L-shaped grooves formed on the sides of said plug, with the horizontal portions thereof adjacent the outer end of said plug; and inwardly extending retaining bosses on the inner walls of said tube formed by radial indentations on the outer walls of said tubular boss positioned to engage in said L-shaped plug grooves and limit said plug to axial movement from a fully extended open position with one end of said diametrical notch in register with said discharge hole, to a closed position with the plug fully inserted, and a locked position with the plug rotated so that said bosses engage in the horizontal portions of said L-shaped grooves.
